UNITED STATES PATENT OFFICE.

ELIZABETH STEWART, OF NEW YORK, N. Y.

FLAT-IRON.

SPECIFICATION forming part of Letters Patent No. 471,361, dated March 22, 1892.

Application filed August 8, 1891. Serial No. 402,075. (No model.)

To all whom it may concern:

Be it known that I, ELIZABETH STEWART, of the city, county, and State of New York, have invented a new and Improved Flat-Iron, of which the following is a specification.

My invention consists in a flat-iron which is at the same time light, capable of being quickly and easily heated, and of such construction as when heated to be useful in pressing ladies' dresses, &c. When constructed in its best form my flat-iron may be heated in a few minutes by merely a tea-spoonful of alcohol and is self-supporting while being heated.

15 In the accompanying drawings, Figure 1 is a perspective view of my flat-iron as it stands while being heated. Fig. 2 is a rear end view. Fig. 3 is a sectional detail on the line $x-x$ of Fig. 2; and Fig. 4 is a transverse section of 20 the iron on the line $y-y$, Fig. 1.

a is the base, which is sufficiently thick to retain the heat and which on its smoothing-surface is properly polished.

b is the top plate, not as thick as the base, 25 but which is otherwise of the same size.

c is a rim extending all around the edge of the top b , from which it projects toward the base a .

30 d are bars connecting the rim c with the base and being separated from each other by sufficient space to admit air. When the iron is inverted, as shown in the drawings, the top b , together with its rim c , forms a pan adapted to contain alcohol, and at the rear the rim c

35 is extended backward at e , so as to provide for conveniently pouring the alcohol into the pan. The flange e is curved toward the bot-

tom of the pan, as shown in Fig. 3, so that whatever alcohol is poured inside the flange e will run down onto the body of the pan. 40

The handle is divided and consists of the four arms f , g , h , and i , the cross-pieces j and k , and the wooden bars l and m . The arms are pivoted to lugs n , cast with the top plate b . Toes o are formed on the arms, so as to 45 bear against the top plate b and prevent the two halves of the handle from separating further than is shown in the drawings.

In using the flat-iron I spread the two parts of the handle and stand the iron upon its 50 handle as a support. I then pour a small quantity of alcohol into the pan formed by the inverted top plate and its rim c . I then ignite the alcohol, and when it is consumed the base-plate a will be found very hot, and 55 the iron is ready for use. The rim c is shown as integral with the top plate b and with the bars d , which are also integral with the plate a , the whole iron being in one piece excepting the handle and the plate b , forming the 60 bottom of the inverted pan, of which the rim c forms the edges; but I do not wish to limit myself to this particular form of construction.

I claim—

As an article of manufacture, a flat-iron 65 having a base-plate, an inverted pan above the same, and a handle adapted to act as a support for the iron in an inverted position, substantially as described.

ELIZABETH STEWART.
